FLUID LIFT

Ivan B. Crocker, Garnett, Kans., and Drannan C. Worthy, Oklahoma City, Okla.

Application December 12, 1936, Serial No. 115,604

1 Claim. (Cl. 103—260)

The present invention has for its objects the provision of novel means for lifting liquid in a well. The invention aims to provide a structure which will employ hot gas or other fluid to lift the liquid. The invention aims, further, to provide a device which will eliminate the coagulation of paraffin, and thereby control the amount of paraffin in the oil, as it comes from the well, the amount of paraffin in the oil being decreased, and the well being given a longer life. Another object of the invention is to supply a novel means whereby the hot gas or other fluid is carried down to the bottom of the well, and then directed upwardly, to lift the liquid in the well.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in elevation, a device constructed in accordance with the invention, parts being in section;

Fig. 2 is a vertical section on an enlarged scale, parts being broken away;

Fig. 3 is a cross section on the line 3—3 of Fig. 2;

Fig. 4 is a cross section on the line 4—4 of Fig. 2.

The numeral 1 marks a pipe, of any desired diameter, through the instrumentality of which, gas, air or other fluid under pressure is delivered to a heater which, as a whole, is designated by the reference letter H. The heater H may be of any desired construction, and in order to regulate the flow of the pressure fluid to the heater H, a valve 2, under the control of an operator, is interposed in the fluid delivery pipe 1, the valve being located outside the heater.

As shown, but by no means of necessity, the heater H embodies a sinuous pipe 4, located within a casing 5 and connected at its lower end to the fluid delivery pipe 1. The loops 6 of the pipe 4 are joined securely together by braces 7. Any suitable means may be furnished for supplying the necessary heat, a burner B being indicated in Fig. 1 of the drawing. The construction of the

burner is left to the discretion of the person installing the device.

The pipe 4 is connected to a pipe 8, in which is interposed a valve 9, the valve 9 being employed to regulate the pressure that is delivered to the well. The valve 9 is under the control of an operator. A pressure gauge 10 is interposed in the pipe 8.

The fluid pressure conduit including the pipe 1, the pipe 4 and the pipe 8, has a depending vertical arm 11 which extends downwardly to a point closely adjacent to the bottom of the well tubing 12. A sleeve 14, defining a fluid chamber, is disposed about the arm 11 and is open at both ends. A check valve 15 is interposed in the arm 11 and is located within the sleeve 14, the check valve serving to prevent liquid from rising in the arm 11 of the pipe 8. The upper end of the sleeve 14 is connected to the pipe 11 by upper braces 16.

Disposed within the sleeve 14, about the arm 11, and spaced from both the arm 11 and the sleeve 14, is a tubular nozzle 17, including a bottom 18 which closes the lower end of the arm 11 of the pipe 8, the bottom closing the lower end of the nozzle 17 also. The nozzle 17 is connected to the arm 11 of the pipe 8 by upper braces 19. The lower end of the nozzle 17 is connected to the sleeve 14 by lower braces 20. Within the tubular nozzle 19, the arm 11 of the pipe 8 is supplied with any desired number of perforations 21.

In practical operation, the gas or air, regulated by the valve 2, moves through the pipe 1, into the heater pipe 4, the air or gas being heated by the burner B or its equivalent. The heated fluid moves through the pipe 8, the pressure being regulated by the valve 9, and the gauge 10 indicating the pressure that is being maintained within the well.

The fluid under pressure moves downwardly through the arm 11 and passes into the nozzle 17 by way of the perforations 21. The fluid under pressure is directed upwardly by the nozzle 17, since the nozzle 17 is closed at its bottom, as shown at 18. The fluid under pressure moves upwardly through the sleeve 14 and carries the liquid with it, the liquid being directed to the top of the well.

The device is simple in construction, but will be found thoroughly effective to carry out and attain the objects set forth in the opening portion of this specification.

Having thus described the invention, what is claimed is:

In a device of the class described, a fluid pressure pipe adapted to be extended downwardly

into a well, a sleeve about the lower portion of the pipe, a nozzle within the sleeve and open at its upper end, the nozzle having an integral transverse bottom integrally closing the lower end of the pipe, the nozzle being shorter than the sleeve, the pipe having perforations establishing communication between the pipe and the nozzle, the sleeve being open at its upper and lower ends, the nozzle and the sleeve each being of a common internal diameter and of a common external diameter from end to end, and at least so much of the pipe as is within the sleeve being of a com-

mon internal diameter and a common external diameter, there being annular spaces, each of a common diameter, from end to end, between the sleeve and the nozzle and between the nozzle and the pipe, a check valve interposed in the pipe and located in the sleeve, above the nozzle, means for securing the sleeve to the pipe, above the check valve, and means for securing the nozzle to the sleeve, below the check valve. 5
